[57] CLAIM

The ornamental design for a riding toy, as shown and described.

DESCRIPTION

FIG. 1 is a top plan view of a riding toy showing my new design;

FIG. 2 is a right side elevational view thereof, the side opposite being substantially a mirror image;

FIG. 3 is a front elevational view thereof;

FIG. 4 is a rear elevational view thereof; and

FIG. 5 is a bottom plan view thereof.

*Fig. 1.**Fig. 3.**Fig. 2.**Fig. 4.**Fig. 5.*
